ELECTRONIC CALCULATING MACHINE

Katsumi Jinbo, Osaka, Japan, assignor to Sharp
Kabushiki Kaisha, Osaka, Japan

Filed Dec. 4, 1972, Ser. No. 311,806

Claims priority, application Japan June 7, 1972

Term of patent 14 years

Int. Cl. D14—02

U.S. Cl. D26—5 C

FIG. 1

FIG. 2

FIG. 3

FIG. 4

FIG.5

FIG.6

FIG.7

FIG. 1 is a front perspective view of an electronic calculating machine showing my new design;

FIG. 2 is a top plan view thereof;

FIG. 3 is a front elevational view thereof;

FIG. 4 is a rear elevational view thereof;

FIG. 5 is a right side elevational view thereof;

FIG. 6 is a left side elevational view thereof; and

FIG. 7 is a bottom plan view thereof.

I claim:

The ornamental design for an electronic calculating machine, as shown.
